CLAIM

The ornamental design for an orthopedic device, as shown and described.

DESCRIPTION

FIG. 1 is a top, left front perspective view of an orthopedic device;

FIG. 2 is a top, right rear perspective view thereof;

FIG. 3 is a bottom, left perspective view thereof;

FIG. 4 is a bottom, right perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a left side view thereof;

FIG. 10 is a right side view thereof; and,

FIG. 11 is a cross-sectional view thereof taken along line 11-11 in FIG. 5.

In the drawings, the broken lines depict portions of the orthopedic device that form no part of the claimed design.
